UNITED STATES PATENT OFFICE.

ANGELO ROBERT CLAS, OF TOLEDO, OHIO, ASSIGNOR TO THE TOLEDO AUTOMOTIVE PRODUCTS COMPANY, A CORPORATION OF OHIO.

WINDOW-CONTROL MECHANISM.

Application filed August 13, 1923. Serial No. 657,059.

To all whom it may concern:

Be it known that I, ANGELO ROBERT CLAS, a citizen of the United States, and a resident of Toledo, in the county of Lucas and State 5 of Ohio, have invented a new and useful Window-Control Mechanism, which invention is fully set forth in the following specification.

This invention relates to window raising 10 and lowering mechanisms, and particularly to those adapted for use in connection with the windows of closed automobiles and other vehicles.

The object of the invention is the provision of a mechanism of this class which is easily and quickly operated to raise or lower an associated window, is composed of a few parts and is capable of being easily 15 and quickly mounted in or removed from a window casing.

The invention is fully described in the following specification, and while in its broader aspect it is capable of embodiments in numerous forms, a preferred embodiment 20 thereof is illustrated in the accompanying drawings, in which,

Fig. 1 is a fragmentary inner side elevation of a window casing embodying the invention, with the associated window, which 25 is partly broken away, in partially raised position. Fig. 2 is a section on the line 2—2 in Fig. 1, and Fig. 3 is an enlarged section on the line 3—3 in Fig. 1.

Referring to the drawings, 1 designates a 30 door or window casing, forming a window opening 2 in its top portion and a chamber 3 in its lower portion. The customary cross-bar or lock board 4 is provided in the door or casing at the inner side of the top portion 35 of the chamber 3, and a glass or other suitable closure member 5 is mounted for vertical movements in the casing to adapt it to enclose the opening 2 or to be lowered in the chamber 3.

The control mechanism for the closure member includes a plate 6, which is screwed or otherwise rigidly secured to the inner side of the cross-bar 4 and carries a pivot stud 7 on which a sector gear 8 is mounted 40 for free pivotal movements in a plane parallel to the plane of raising and lowering movements of the window member. The plate 6 has a portion 9 extending below the cross-bar 4, and pivoted to this extension at 45 10 is a lever member 11 carrying a roller 12

or other suitable support at its outer end on which the lower edge of the window member 5 rests. An arm 13 projects from the hub portion of the gear 8 in opposition to its toothed portion and is connected by a 50 link 14 to the lever 11 at a point adjacent to the pivot 10 and preferably between such pivot and the point of engagement of the lever with the window member. It is thus evident that any turning movement of the 55 sector gear 8 will be communicated to the lever 11 through the link 14 and effect a raising or lowering of the window member 5, as the case may be. It is important, however, that the points of connection of the 60 link 14 with the arm 13 and lever 11 be the same distance from the pivotal center of one as the other.

The weight of the window member on the lever 11 is counterbalanced by a coiled contractile spring 15, which is connected at one end to an extended inner end of the lever and at its other end to a bracket 16 secured to the casing 1 and projecting into the lower portion of the chamber 3.

The sector gear 8 is engaged by a drive pinion 17 which is mounted on the inner end of a shaft 18 for turning movements therewith. This shaft projects through the plate 6 and cross-bar 4, being journaled in a suitable sleeve member 19, and is adapted to receive a control handle (not shown) at its outer end. The pin 20, which secures the pinion 17 to the shaft 18, projects at its ends into a substantially V-shaped notch 21 in the outer hub end of the pinion, and a coiled compression spring 22 is mounted on the shaft between the sleeve 19 and pinion, and normally forces the pinion outward on the shaft so that the pin seats within the apex 90 portion of the notch 21. A lock finger 23 is fixed to the plate 6 and engages one or more teeth of the pinion 17 when the pinion is at the limit of its outward movement with respect to the shaft 18. Upon a turning of 95 the shaft 18 in either direction the pin 20 first acts on the inclined sides of the notch 21 to force the pinion inward against the tension of the spring 22 and out of locking engagement with the finger 23 and a continued turning movement of the shaft will then cause the pinion to turn therewith and impart a turned movement to the sector gear 8. As soon as the shaft 18 is relieved of the 100 turning force the pinion 17 will assume its 105 110

normal position on the shaft and interengage with the finger 23 to lock the window control parts against further movement.

It is evident that I have provided a simple and efficient window control mechanism that is easily operable to raise or lower an associated window, due to the relative difference in sizes of the drive pinion 17 and sector gear 18, and that the parts are automatically locked in any position when the control handle or member is relieved of the turning force.

I wish it understood that my invention is not limited to any specific construction, arrangement or form of the parts, as it is capable of numerous modifications and changes without departing from the spirit of the claim.

Having thus described my invention, what I claim as new, and desire to secure by Letters Patent, is:

In a window control mechanism, a support adapted to be attached to the lock board of a window casing, a lever pivoted intermediate its ends to said support and normally extending in substantially a horizontal plane, one end of said lever being adapted operatively to engage an edge of the window, a spring connected to said lever and adapted to be connected at the opposite end thereof to a stationary point within the casing, a link movably connected to said lever between the window engaging end and pivot thereof, and interengaging toothed elements on said support and connected to one end of said link whereby actuation of said elements in one direction or the other raises or lowers the window.

In testimony whereof, I have hereunto signed my name to this specification.

ANGELO ROBERT CLAS.
